UNITED STATES PATENT OFFICE.

GEORGE H. GIBSON, OF MONTCLAIR, NEW JERSEY, ASSIGNOR TO HARRISON SAFETY BOILER WORKS, OF PHILADELPHIA, PENNSYLVANIA, A COPARTNERSHIP.

APPARATUS FOR HEATING WATER.

1,119,819.

Specification of Letters Patent.

Patented Dec. 8, 1914.

Application filed December 13, 1910. Serial No. 597,036.

To all whom it may concern:

Be it known that I, GEORGE H. GIBSON, a citizen of the United States, residing at Montclair, county of Essex, and State of New Jersey, have invented certain new and useful Improvements in Apparatus for Heating Water, of which the following is a specification.

This invention relates to apparatus for heating water and is directed particularly to the provision of apparatus of this character adapted for use in round-houses and similar structures for supplying water for filling and washing the boilers of locomotives.

The object of the invention is to provide an apparatus for this use which is reliable and efficient in operation, which is economical in that it utilizes the heat in the blow-off of the locomotive, which can be manufactured and installed at comparatively small expense and which is convenient to use.

In emptying, washing and filling locomotive boilers it is highly desirable to save the heat in the blow-off since in this way a substantial economy is effected, and this can be conveniently done by transferring the heat contained in the blow-off, or a portion thereof, to the water which is to be utilized in either or both washing and filling.

The blow-off of the locomotive consists of both steam and hot water, but when a locomotive boiler requires washing and filling the water in the locomotive is usually so impure that it is inadvisable to return it along with other water to the boiler. The steam, however, can well be utilized and the condensation thereof along with other water supplied to a boiler in washing and filling the same. If the blow-off of a locomotive be separated into the steam and water, the steam utilized and the water thrown away, an amount of heat units will be wasted equivalent to the amount necessary to raise the blow-off water from the temperature of the supply water to 212° F. With supply water at 60° this will amount to a difference in temperature of 152°.

The present invention involves the provision of apparatus for utilizing the heat in the blow-off for heating either or both washing and filling water without directly employing the water of the blow-off, but obtaining from the blow-off more of the heat

units therein than is represented by the blow-off steam or by the difference between the temperature of the blow-off and 212° F. The water of the blow-off is allowed to run to waste but only after its temperature has been reduced far below that at which it liberates steam under atmospheric pressure and the heat obtained in so reducing the temperature of the blow-off water is transferred to the water to be heated. The operation is therefore far more economical than one in which the steam and water of the blow-off are separated and the water at approximately 212 degrees thrown away, for, in accordance with the present invention, the blow-off water before being thrown away is reduced to a temperature substantially lower than 212 degrees, and the heat units thus obtained are utilized in the water to be heated.

The invention contemplates the employment of a jet condenser into which steam from the blow-off is carried and mixed with supply water, so as to heat the latter to the temperature desired for washing and filling water. This jet condenser is connected directly to the boiler of a locomotive which is to be emptied or to a suitable closed receptacle into which the entire fluid contents of a locomotive boiler are emptied, and in the operation of the apparatus a vacuum is formed in the condenser as is usual in the operation of such apparatus which aids in drawing the steam into the condenser. By reason of the formation of a vacuum in the condenser, the latter receives not only the steam which was present as such in the locomotive boiler at the time of beginning the blow-off operation but it also draws additional steam from the hot water in the locomotive boiler until the temperature of that water has been reduced far below a temperature at which steam is liberated under normal conditions, the temperature of the blow-off water being reduced during this operation from 212 degrees to a temperature substantially lower, depending upon the degree of vacuum formed in the condenser. The operation may be continued thus until, due to the extraction of heat from the blow-off water, that water has been greatly reduced in temperature and the water may then be allowed to run to waste since then but a comparatively small amount of heat will be wasted.

The heated water flowing from the condenser may be carried to a tank or heater and water may be drawn therefrom for either or both washing and filling purposes, 5 the water for washing in that case being mixed with cold water so that it will be at the temperature desired for washing; or if desired, two tanks or heaters may be arranged to be supplied with water flowing 10 from the condenser, one of these tanks to contain washing water and the other filling water. In either case automatic controlling devices may be employed whereby the water admitted to the heaters or tanks will be at 15 substantially the desired temperature.

The principles of my invention may be employed in various forms of apparatus.

I have illustrated in the accompanying drawings two forms in which the invention 20 may be practised, these two being shown in Figures 1 and 2 diagrammatically.

Referring first to Fig. 1, a blow-off pipe is indicated at 1 arranged for connection with a boiler of a locomotive 2 which is to 25 be emptied. The connection to the boiler may be effected in any suitable manner as by means of a flexible hose 3, this hose connecting with the upper portion of the boiler, as for instance the steam dome or safety- 30 valve connection, so that when the passage through the pipe 1 is opened, as by means of the manually operated valve 4, steam from the boiler will pass through the pipe. Pipe 1 may extend completely around a 35 round-house so that connection can be made to it from any one of the locomotives therein. The other end of pipe 1 is connected to a jet condenser 5 so that the steam passing through the pipe will flow into the condenser. Condenser 5 is also supplied with 40 cold water from a pipe 6. The condenser is of the usual or any suitable construction so arranged that steam and water entering the condenser through the pipes 1 and 6 will 45 become mingled, the water heated by the steam and the steam condensed. The water thus heated flows from the condenser through the tail-pipe 7 provided with a manually operated valve 8. Means are 50 provided for receiving the water flowing from the condenser and also suitable controlling devices whereby the temperature of this water will be regulated as hereinafter described.

55 When a locomotive boiler is connected to the condenser 5 by means of the pipe 1 and the passage through the pipe opened, steam will flow from the boiler into the condenser where it will become mingled with the water entering the condenser through the pipe 6 and the temperature of the water will be raised, the water flowing out through the tail-pipe. During the operation of the condenser a vacuum is formed therein due 60 to the rapid condensation of the steam and

this vacuum assists in drawing the steam from the boiler into the condenser. As the steam which was present as such in the boiler at the time the connection to the condenser was opened passes into the condenser, 70 steam will be drawn off from the hot water in the boiler by reason of the reduction of the pressure, and because of the presence of the vacuum in the condenser 5, operation in this manner will continue until the temperature of the water in the boiler has been carried down considerably below 212 degrees, 75 an amount depending upon the degree of vacuum existing in the condenser. After the temperature of the water in the boiler has been reduced thus, this water is allowed to run out from the boiler to waste. It will be seen, therefore, that the heat units in the blow-off of the locomotive have been utilized 80 in heating water in the condenser 5 to an extent represented by the difference between the heat units in the original blow-off and the heat units remaining in the blow-off water when it is allowed to run to waste. Furthermore, it will be noted that the heating 85 of the water which is to be afterward utilized in the boiler is accomplished without mingling with that water the impure water removed from the boiler.

In Fig. 1 the tail-pipe 7 is shown as provided with two branch pipes 9 and 10, the former leading to a reservoir 11 for filling water and the latter leading to a reservoir 12 for washing water. The pipes 9 and 10 are provided with manually operated valves 95 13 and 14 respectively. In the apparatus illustrated, the reservoir 11 consists of a feed-water heater provided with trays 15 over which the water admitted by pipe 13 flows and a steam inlet 16 for carrying to 100 the heater 11 exhaust steam from stationary engines and similar devices to additionally heat the water entering the heater. An oil separator 17 is provided in the steam pipe 16 and a trap 18 as is usual in feed-water 105 heaters of this type. Projecting into the tail-pipe 7 is a thermometer 19 to indicate the temperature of the water passing therethrough and a thermostat 20. This thermostat 20 forms part of a controlling system 110 whereby the temperature of the water flowing from the condenser is regulated. The thermostat 20 operates in any suitable manner, as through the link 21, to position the movable member 22 of a master-valve 23. 115

In the steam pipe 1 is a valve 24 automatically actuated by a piston movable in a cylinder 25. This cylinder is supplied at one end with water through the pipe 26, the entrance into this pipe being controlled by the thermostatically operated master-valve 23. The valve 23 is also connected by a pipe 27 with cylinders 28 and 29 for operating valves 30 and 31 in the pipes 9 and 10 respectively, the connections to the cylinders 120 125 130

28 and 29 being at opposite ends thereof so that the admission of water under pressure to pipe 27 tends to close valve 30 and open valve 31. The cylinders 28 and 29 have 5 springs therein engaging the pistons which operate the movable members of the valves 30 and 31 for moving those pistons in the directions opposite to those in which they are moved by water admitted through pipe 10 27. The master-valve 23 is also connected by pipe 32 to a cylinder 33 for operating valve 34 in the water pipe 6 so as to move that valve to the closed position as indicated in the drawing; a spring may be arranged in 15 cylinder 33 to move the valve to the open position. Pipe 32 is also connected by pipe 35 to the cylinder 25 at the end of that cylinder opposite that to which the pipe 26 is connected so that water admitted to cylinder 25 through pipe 35 will tend to close valve 24 and this closing movement may be assisted by a spring in cylinder 25. Water under pressure is admitted to the cylinder of the master-valve 23 through a pipe 36. 20 Valve 24 in the steam pipe 1 may be so arranged that when moved the maximum distance by the spring in the cylinder 25 or by water admitted through pipe 35, or both, it will not entirely close the passageway for 25 steam through pipe 1. The operation of this controlling mechanism will now be described.

When the operation of heating water in condenser 5 with the blow-off steam is commenced, the steam is at its highest temperature and therefore need be admitted to the condenser at the lowest rate. The valve 24 is therefore almost closed and the valve 34 in the water pipe 6 is wide open. Water 30 and steam are admitted through pipes 6 and 1 respectively by opening the manually operated valves 37 and 4 so that steam and water flow into the condenser 5, the water becomes heated and the steam condensed 35 and hot water flows out through pipe 7. This hot water acts upon the thermostat 20 which operates the movable member 22 of the master-valve 23 to an extent corresponding to the temperature of the tail-water 40 flowing out through pipe 7. When beginning the operation the valve 30 is opened and the valve 31 closed so the water flowing from the condenser passes through pipe 9 to the heater and reservoir 11. This water 45 is to be used as filling water and therefore should be at a temperature of approximately 212 degrees. To accomplish this the thermostat 20 will be so arranged that if the temperature of the water flowing through 50 pipe 7 falls below 212 degrees water under pressure will be admitted by the valve 23 from the pipe 36 to the pipe 26 and this water passing into the cylinder 25 will open the valve 24 slowly to admit more steam to 55 the condenser 5 and thus raise the tempera- 60 ture of the water flowing from the condenser to the desired point. Operation will continue in this way with the thermostat regulating the amount of steam admitted to the condenser so as to keep the temperature of the water flowing from the condenser substantially uniform until valve 24 has been opened to its full extent. From this point on the temperature of the water flowing from the condenser will fall as the temperature of the steam admitted falls, until a point is reached at which it will be desired to discontinue the supplying of water to the reservoir 11, due to the comparatively low temperature of that water. When such a point has been reached the thermostat 20 will have moved the movable member of the valve 23 to such point that water will be admitted from pipe 36 through pipe 27 to the cylinders 28 and 29 at opposite ends of the latter and this will result in the closing of valve 30 and the opening of valve 31. The water flowing from the condenser will then pass through pipe 10 to the reservoir 12 for washing water and the operation in this way will continue with the temperature of the water supplied to reservoir 12 falling steadily as the temperature of the steam passing into the condenser 5 falls. The temperature desired for the washing water in tank 12 is 65 about 120 degrees and therefore the operation will be continued until that temperature of the water in tank 12 has been reached whereupon the operation of the mechanism will be automatically discontinued by shutting off the supply of water and steam to the condenser. This is effected by the thermostat 20 when the temperature of the water in pipe 7 falls to a predetermined point by 70 causing the valve 23 to admit water under pressure from pipe 36 through pipe 32 to the cylinders 33 and 25 in such manner that the valves 34 and 24 are moved to the closed position. The manually operated valves 37 and 4 are then closed. It will thus be seen that automatic operation is secured whereby water is heated in the condenser to the temperature desired for filling water and is carried to the reservoir for filling water as 75 long as steam is available for heating water to this temperature, whereupon the connections are so changed that the heated water is diverted into the tank for washing water and that at the end of the operation the 80 connections to the condenser are automatically closed.

Fig. 2 shows an apparatus similar to that illustrated in Fig. 1 in that a jet condenser is employed for heating the water but differing in that but a single reservoir is employed for the heated water and in that an intermediate receptacle is employed for receiving the fluid contents of the locomotive boiler before the steam thereof is carried to the 85

condenser. Referring to this figure, 38 indicates a chamber in the form of a steam separator which is adapted to be connected by a pipe 39 to the blow-off cock of a locomotive. A pipe 1 connects this chamber 38 to the condenser 5. The pipe 7 leads from the condenser to a feed-water heater and reservoir 11 and the thermostat 20 projects into this pipe and controls the operation of a master-valve 23 adapted to regulate the flow of steam through pipe 1 by controlling the operation of valve 24 in that pipe as described in connection with Fig. 1. Filling water is drawn from the reservoir 11 through a pipe 40 as in the apparatus illustrated in Fig. 1, but to provide washing water, the hot water in the reservoir 11 is drawn off and mixed with a suitable quantity of cold water. For this purpose a pipe 41 is shown connected to the reservoir 11 and leading to one cylinder 42 of a pump. The other cylinder 43 of the pump has a cold water pipe 44 connected thereto. The pipes 45 and 46 leading from the cylinders 42 and 43 respectively are connected as shown, so that the water passing through them becomes mixed and the temperature of the hot water reduced. In order to permit of regulating the temperature of this mixture of hot and cold water as desired for washing the locomotive boilers, a by-pass 47 around the cylinder 43 is provided and a throttle valve 48 is inserted in this by-pass so that more or less of the water passing through cylinder 43 may be allowed to return from the discharge end to the suction end as may be necessary. The pistons in the cylinders 42 and 43 are operated together as by mounting them on the piston rod of a piston moving in a steam cylinder 49. It is desired a mixing chamber 50 may be inserted in the pipe 51 for carrying the washing water to insure proper mixing of the hot and cold water passing through that pipe.

In operating with the apparatus illustrated in Fig. 2, the thermostatic regulating device will so regulate the entrance of steam into the condenser 5 that the water passing from the condenser will be at a substantially uniform temperature, this being the temperature desired for the filling water. As shown the passage of steam through pipe 1 would be shut off manually by operating the valve 4 when by reason of the fall in the temperature of the steam the temperature of the water flowing from the condenser is substantially below that desired for the filling water, but this can be accomplished automatically if such automatic operation be desired in the manner illustrated in Fig. 1 and above described.

Having described my invention, what I claim as new therein and desire to secure by Letters Patent of the United States is:

65 1. Apparatus for discharging locomotive

boilers and supplying water thereto comprising the combination of a pipe adapted to be connected to the boiler of a locomotive, a jet condenser connected to said pipe and receiving steam from the boiler therethrough, a water-supply pipe connected to the condenser for carrying water to be heated thereto, a receiver for the heated water flowing from the condenser, and thermostatic means governed by the temperature of the water flowing from the condenser for admitting an increasingly larger proportion of steam to the condenser as the temperature and pressure drop in the boiler, substantially as set forth. 80

2. Apparatus for discharging locomotive boilers and supplying water thereto comprising the combination of a pipe adapted to be connected to the boiler of a locomotive, a jet condenser connected to said pipe and receiving steam from the boiler therethrough, a water-supply pipe connected to the condenser for carrying water to be heated thereto, a reservoir for the heated water flowing from the condenser, means for maintaining the temperature of the water flowing from the condenser substantially uniform for a period during discharge of steam from the boiler, and means for automatically cutting off the supply of steam and water to the condenser when the temperature of the water flowing from the condenser has subsequently fallen below a determined amount, substantially as set forth. 90

3. Apparatus for discharging locomotive boilers and supplying water thereto comprising the combination of a pipe adapted to be connected to the boiler of a locomotive, a jet condenser connected to said pipe and receiving steam from the boiler therethrough, a water-supply pipe connected to the condenser for carrying water to be heated thereto, a reservoir for the heated water flowing from the condenser, valves in said steam and water pipes, automatic means for progressively opening said steam supply valve as the discharge from the boiler proceeds, governed by the temperature of the water flowing from the condenser until said valve is fully open, and automatic means for subsequently closing said water supply valve, substantially as set forth. 100

4. Apparatus for discharging locomotive boilers and supplying water thereto comprising the combination of a pipe adapted to be connected to the boiler of a locomotive, a jet condenser connected to said pipe and receiving steam from the boiler therethrough, a water supply pipe connected to the condenser for carrying water to be heated thereto, a reservoir for the heated water flowing from the condenser, valves in said steam and water pipes and automatic means for closing said valves when the temperature of water flowing from said condenser drops. 110

below a predetermined value, substantially as set forth.

5. Apparatus for discharging locomotive boilers and supplying water thereto comprising the combination of a pipe adapted to be connected to the boiler of a locomotive, a jet condenser connected to said pipe and receiving steam from the boiler therethrough, a water-supply pipe connected to the condenser for carrying water to be heated thereto, two receivers for the heated water connected to the condenser, and automatic means for directing the water flowing from the condenser into one or the other of said receivers in accordance with the temperature thereof, and for shutting off the supply of steam and water to said condenser when the temperature of the water flowing from the condenser drops below a predetermined amount, substantially as set forth.

6. Apparatus for discharging locomotive boilers and supplying water thereto comprising the combination of a pipe adapted to be connected to the boiler of a locomotive, a jet condenser connected to said pipe and receiving steam from the boiler therethrough, a water supply pipe connected to the condenser, two receivers for the water flowing from the condenser, and automatic devices operating in response to changes of temperature of the water flowing from the condenser for disconnecting one of said receivers from the condenser and connecting the other thereto, substantially as set forth.

7. Apparatus for discharging locomotive boilers and supplying water thereto comprising the combination of a pipe adapted to be connected to the boiler of a locomotive, a jet condenser connected to said pipe and receiving steam from the boiler therethrough, a water supply pipe connected to the condenser for carrying water to be heated thereto, a receiver for the heated water flowing from the condenser, and automatic devices operating in response to a lowering in temperature of the water flowing from

the condenser for disconnecting the receiver from the condenser when the temperature of the water flowing from the condenser has fallen to a predetermined value, substantially as set forth.

8. Apparatus for discharging locomotive boilers and supplying water thereto comprising the combination of a pipe adapted to be connected to the boiler of a locomotive, a jet condenser connected to said pipe and receiving steam from the boiler therethrough, a water supply pipe connected to the condenser for carrying water to be heated thereto, a reservoir for the heated water flowing from the condenser, a valve in said steam pipe, automatic means for progressively opening said valve as the discharge from the boiler proceeds, governed by the temperature of the water flowing from the condenser, until said valve is fully open, and automatic means for subsequently disconnecting the receiver from the condenser, substantially as set forth.

9. Apparatus for discharging locomotive boilers and supplying water thereto comprising the combination of a pipe adapted to be connected to the boiler of a locomotive, a jet condenser connected to said pipe and receiving steam from the boiler therethrough, a water supply pipe connected to the condenser for carrying water to be heated thereto, two receivers for the water flowing from the condenser, and automatic devices operating in response to progressive lowering of the temperature of the water flowing from the condenser for first disconnecting one of said receivers from the condenser and connecting the other thereto and subsequently for shutting off the supply of steam and water to said condenser, substantially as set forth.

This specification signed and witnessed this 29th day of November, 1910.
